(57) **CLAIM**

The ornamental design for an all sports sun visor, as shown and described.

DESCRIPTION

FIG. 1 is a front perspective view of an embodiment of the all sports sun visor;

FIG. 2 is a rear perspective view thereof;

FIG. 3 is a top view thereof in which the claimed design is shown in a flattened configuration, the bottom view being the mirror image thereof;

FIG. 4 is a left side view thereof;

FIG. 5 is a right side view thereof; and,

FIG. 6 is a front view thereof.

The crown of a baseball-style cap shown in broken lines in the drawings illustrates environmental matter and forms no part of the claimed design.
